CLAIM

The ornamental design for a salad spinner, as shown and described.

DESCRIPTION

FIG. 1 is a top, right side and rear perspective view of a salad spinner showing our new design;

FIG. 2 is a top plan view thereof;

FIG. 3 is a bottom plan view thereof;

FIG. 4 is a rear elevation view thereof;

FIG. 5 is a front elevation view thereof; and,

FIG. 6 is a left side elevation view, the right side being a mirror image thereof.
